(57) **CLAIM**

The ornamental design for a tub for bathing, as shown and described.

DESCRIPTION

FIG. 1 is a perspective view from the front, above and to the left of the tub for bathing which is the subject of our new design;

FIG. 2 is a top plan view thereof;

FIG. 3 is a front elevational view thereof, the rear elevational view being a mirror image thereof;

FIG. 4 is a right side elevational view thereof, the left side elevational view being a mirror image thereof; and,

FIG. 5 is a bottom plan view thereof.

The portions shown in broken lines in the drawings form no part of the claimed design.
